United States Patent Office.

SAMUEL L. BLIGH, OF SANDY LAKE, PENNSYLVANIA.

Letters Patent No. 106,311, dated August 16, 1870.

IMPROVED HAND CORN-HUSKER.

The Schedule referred to in these Letters Patent and making part of the same.

To all whom it may concern;

Be it known that I, SAMUEL L. BLIGH, of Sandy Lake, in the county of Mercer and State of Pennsylvania, have invented a new and Improved Corn-Husker; and I do hereby declare that the following is a full, clear, and exact description thereof, which will enable others skilled in the art to make and use the same, reference being had to the accompanying drawing forming part of this specification, in which the drawing represents a perspective view of my improved corn-husker.

The object of this invention is to construct an instrument by means of which the husking of corn can be accomplished in an easy and expeditious manner.

The invention consists in the new arrangement of a pair of circular shears and hooks, whereby the husk is cut and torn, to be readily separated from the ear, which, by another cutter, is severed from the stem.

A, in the drawing, represents the handle of my improved corn-husker. From it projects a metal plate, B, which has, at its end, two projecting fangs or blades, *a* and *b*, that have cutting-edges *c* formed on them on opposite sides.

To the face of the plate B is, by a pin, *d*, pivoted a knife, D, which, with its curved cutting-edge *e*, is opposite the fixed blade *a*, to form a pair of shears with the same.

To the opposite side of the plate B is pivoted another knife, E, whose curved cutting-edge *f* is opposite the blade *b*, to operate in conjunction with the same.

A spring, *g*, may be applied for the purpose of holding the shear E *b* open.

h are hooks or prongs projecting from the blade *b*, for the purpose of tearing the husk.

To use the instrument, it is grasped in the right hand, with the thumb in or on the handle *i* of the knife E, and one finger in the handle *j* of the knife D.

The butt of the ear of corn is now inserted in such manner that the knife D will close against the stem near the butt, while the knife E embraces the thick part of the butt.

The thumb is first used to apply the shears E *b*. At the same time the instrument is turned so that the shears E *b* will cut through the husk, while the hooks *h* tear the same loose from the corn, which can then be thrown off by the left hand, which held the husk at the point of the ear. The knife D is then pressed against the blade *a*, to sever the ear from the stem.

Having thus described my invention,

I claim as new and desire to secure by Letters Patent—

The hand corn-husker herein described, consisting of the plate B, knives D E, and hooks *h*, all constructed substantially as specified, and arranged to operate in the manner set forth.

SAM'L. L. BLIGH.
